UNITED STATES PATENT OFFICE

WALTER P. HAYTHORN, OF OGALLALA, NEBRASKA

GATE SECURING MEANS

Application filed March 25, 1932. Serial No. 601,238.

The present invention relates to securing means for gates of the type including a plurality of strands of wire having one end anchored to a stationary post and their other ends secured to a movable bar adapted to be, in turn, detachably connected with another post and has for some of its objects to provide, in a manner as hereinafter set forth, a gate securing means which will be simple in construction, strong, durable, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in elevation of a securing means in accordance with this invention operatively engaged with a gate.

Figure 2 is a view in horizontal section, taken substantially on the line 2—2 of Figure 1.

Figure 3 is a top plan view of the securing means.

Figure 4 is a view in top plan showing the securing means being swung toward operative position.

Figure 5 is a detail view in vertical section, taken substantially on the line 5—5 of Figure 4.

Referring now to the drawings in detail, it will be seen that the reference numeral 1 designates generally a conventional gate comprising a plurality of strands of barbed wire 2 having one end anchored to a fence post 3. The other ends of the strands 2 are anchored to a movable bar 4 the lower end of which, when the gate is closed, is engaged in a loop 5 which is mounted on the lower portion of another fence post 6.

The embodiment of the present invention which is illustrated in the drawings comprises an elongated lever 7 having one end portion twisted and curved in a manner to provide a fulcrum portion 8 which is detachably engageable with the gate bar 4.

An arcuate link 9 is pivotally connected to the lever 7 adjacent the hook 8. A chain 10 is connected to the free end of the link 9 by a swivel coupling 11. A hook 12 or other securing means is provided on the free end of the chain 10. The chain 10 is looped around the post 6 and secured in the manner illustrated to advantage in Figures 3 and 4 of the drawings for connecting the lever to said post 6.

Formed integrally with the free end of the lever 7 and disposed at right angles thereto are upper and lower opposed hooks 14 the ends of which are separated by an intervening space as best shown in Figure 5. When the lever 7 is swung from the position shown in Figure 4 to the position shown in Figure 3 the uppermost strand 2 of the gate 1 is received between the said upper and lower hooks, and when the lever 7 is so engaged with said strand 2 disengagement of the said lever 7 from the strand 2 by upward movement of the lever 7 is prevented by the lower hook 13, it being noticed in this connection that normally the upper hook 13 supports the lever 7 on the strand 2 and at the same time prevents disconnection of the free end of the lever 7 from the strand 2 except when the space between the ends of the hook 13 is opposite the strand 2 and the free end of the lever 7 is swung laterally from the strand 2. It will also be understood that when the gate is fastened the tendency of the lever 7 is to swing toward the position shown in Figure 4, and such tendency, when the lever 7 is engaged with the strand 2 as shown in Figure 3, will tend to prevent casual disengagement of the free end of the lever 7 from the strand 2. A handle 15 is mounted on the free end portion of the lever 7. As seen in Figure 5 of the drawings, the lever 7 is of tubular material.

In use, the hook 8 is engaged with the gate bar 4 in the manner illustrated to advantage in Figure 4 of the drawings and the lever 7 is then swung toward the gate and one of the hooks 14 engaged with the uppermost strand of said gate for securing the lever against swinging movement. In this manner the gate is drawn taut and the bar 4

is embraced between the hook 8 and the arcuate link 9, as seen in Figure 3 of the drawings.

It is believed that the many advantages of a securing means constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

15 The herein described gate securing means consisting essentially of a lever having at its forward end curvilinear fulcrum means and also having at its rear end opposed hooks disposed at right angles to the lever and provided with free ends separated by an intervening space, their heel ends being disposed above and below the lever, and means connected to the lever adjacent to said fulcrum means and adapted for the connection of 25 the lever to a fence post.

In testimony whereof I affix my signature.

WALTER P. HAYTHORN.
